(57) **CLAIM**

The ornamental design for an electric connector, as shown and described.

DESCRIPTION

FIG. 1 is a perspective view of an electric connector showing my/our new design;

FIG. 2 is a front view thereof;

FIG. 3 is a rear view thereof;

FIG. 4 is a top view thereof;

FIG. 5 is a bottom view thereof;

FIG. 6 is a right-side view thereof; and,

FIG. 7 is a left-side view thereof.

The broken lines depict portions of the electric connector that form no part of the claim.
